A. A. MELLOR.
 ATTACHMENT FOR UNLOADING APPARATUS.
 APPLICATION FILED DEC. 28, 1914.

1,196,261.

Patented Aug. 29, 1916.

UNITED STATES PATENT OFFICE.

ALFRED AYRE MELLOR, OF MONTREAL, QUEBEC, CANADA.

ATTACHMENT FOR UNLOADING APPARATUS.

1,196,261.

Specification of Letters Patent. Patented Aug. 29, 1916.

Application filed December 28, 1914. Serial No. 879,366.

To all whom it may concern:

Be it known that I, ALFRED AYRE MELLOR, a subject of the King of Great Britain, and resident of 400 St. James street, in the city of Montreal, Province of Quebec, in the Dominion of Canada, have invented certain new and useful Improvements in Attachments for Unloading Apparatus, as described in the following specification, which is a full, clear, and exact description of the same.

The invention relates to improvements in attachments for unloading apparatus as described in the present specification and illustrated in the accompanying drawings that form part of the same.

The invention consists essentially in the novel means employed for directing the material from a vehicle and depositing it as desired during unloading operations.

The objects of the invention are to devise an apparatus that will facilitate the discharge of a load from vehicles, particularly railway cars containing loose material, and at the same time avoid any interference with the means of unloading, to effect a reduction in expense of labor in such operations, to lessen the period of time required for distributing the material deposited and generally to provide an apparatus of a durable nature that will not be in the way during the ordinary travel of the vehicle and which will be simple to operate and cheap to manufacture.

In the drawings, Figure 1 is a vertical sectional view along the center line of unloading plow showing frame applied thereon to which the improved device is fixed. Fig. 2 is a side elevation of unloading plow showing the invention affixed thereto. Fig. 3 is a cross section on line 3-3 showing plow and the invention in elevation. Fig. 4 is a half plan view of the invention and half sectional view on line 4-4 of Fig. 3.

Like numerals of reference indicate corresponding parts in each figure.

The numeral 1 indicates a railway car of the type used for ballast, loose earth, sand or like material, such cars being used largely in railway construction, the various cars of a train being connected at their open ends by plates or gangways, so that there is an uninterrupted passage from one end of the train to the other. After each car is loaded and the train hauled to its destination, the material is deposited by an unloading plow of any suitable type and which is drawn

from one end of the train to the other, subsequent of course to the opening of the side doors in the walls of said cars. This practice has been carried on for many years and in all its details is well known to those versed in the art.

There are single and double plows, that is to say, plows for unloading one side of the car and plows for unloading at both sides simultaneously. The double plow is illustrated in the accompanying drawings, though this invention is equally efficient as an attachment to a single plow, the difference being that one flash board is used instead of two. The flash boards or plates are supported by frames from the plow and in the drawing the numeral 2 indicates the two rear or main mold boards while 3 indicates the mold boards of a pilot plow, and as these parts of the plow are those that most intimately concern this invention, the plow frame and braces will not be described herein, it being sufficient to say that these mold boards are properly and rigidly held by frames in such a manner that they can be drawn from one end of the train to the other and clear the earth, sand, gravel or other material from the sides of the cars through the side door ways.

The flash boards or plates 4 are pivotally supported at the lower ends of the connecting bars 5, the latter being in pairs and preferably in angle form. The said bars 5 are joined to the flash boards 4 by means of the angle bars 6 extending across the boards 4 at intervals.

The adjusting bars 7 are pivotally secured at the inner edge of the flash boards 4 and each has a row of holes 8 therethrough. The said bars 7 extend outwardly between the members of each pair of bars 5, though it is not necessary to have an adjusting bar for every support, still it is preferable.

The adjusting bars 7 are held in the desired position between the bars 5 by the pins 9, this position being changed according to the material and the work at the place of the discharge. The connecting bars 5 at their upper ends are pivotally joined to the brackets 10, said brackets being of plate form and having the vertical rows of holes 11 and 12, both extending from the pivot 13 at the lower end joining the bars to the brackets so that the flash boards 4 may be further adjusted in their positions by the use of one or other of said rows of holes as

the case may be, and in the lower and working position of the flash boards, pins are inserted through corresponding holes in the connecting bars 5 into and through the 5 bracket holes, thus holding the bars perfectly rigid in respect to the brackets so long as the unloading operation continues. The brackets 10 are rigidly secured to the arms 14 by the bolts 15 and the said arms 10 at their inner ends are secured to the pivots 16, the latter being rigid with the cross beams 17 of a supporting frame.

The cross beams 17 are rigidly secured to the longitudinal beams 18 and this frame 15 formed of the longitudinal and cross beams, is pivotally supported at its front end from the pilot mold boards 3 and toward its rear from the main mold boards 2. The uprights 19 are rigidly secured to the pilot mold 20 boards 3 and support the cross bar 20, to which the forward cross bar of the pivoted frame is secured by the pivot 21.

The uprights 22, 23 and 24 are rigidly secured to the main mold boards 2 and each 25 pair of said uprights support corresponding cross bars, the center cross bar 25 being joined to a cross beam 17 of the upper frame by a pivot 26, the rear pivot joint being reinforced by the diagonal braces 27. The 30 posts 28 are secured to the cross beams 17 by the angle brackets 29 and from their upper ends carry the block and tackle 30 for raising and lowering the arms 14, consequently the connecting bars 5, brackets 10 35 and flash boards 4 are lifted and lowered by said tackle, said connecting bars 5 being first relieved from their pin connection with the brackets 10 and allowed to swing on their pivotal connection with said brackets thus 40 in their upper position the flash boards will rest on the cross beams 17, which is plainly shown in Fig. 3, the arms 14 being in a vertical position. The positions of the brackets 10 change consequent upon the 45 change of the position of the said arms 14, to which they are rigidly attached and the positions of the connecting bars 5 still remain vertical and carry the flash boards 4 at their lower ends on the cross beams 17. The parts will all fall into place very naturally 50 on lowering the arms 14, and connecting bars 5 to the brackets 10, to which they are pinned through one or other of the vertical rows of holes. The flash boards are 55 then adjusted by means of the bars 7 and pinned to the required slant. As the plow moves forward the mold boards of the plow throw the material off the side of the car and this material is guided by the flash 60 boards away from the track and the line of travel of the vehicle.

The device is of inestimable value in unloading work and is intimately associated with the work of an unloading plow, 65 though other uses may be found for it, also

the parts may be arranged and constructed differently so long as the main elements remain as set forth in the claims for novelty following.

What I claim is:

1. In flash boards for unloading apparatus, a frame having posts extending upwardly therefrom, and a plurality of cross and longitudinal beams, suitable supports for said frame, arms extending outwardly 75 from the lower ends of said posts and pivotally secured at their inner ends, connecting bars pivotally joined to and supported from the outer ends of said arms, a flash board or plate pivotally joined to the lower ends of said connecting bars and a block and tackle connecting the outer ends of said arms with the upper ends of said posts for raising and lowering said arms.

2. In flash boards for unloading apparatus, a frame formed of cross and longitudinal beams and posts projecting upwardly therefrom, a frame supporting the aforesaid frame, arms extending outwardly from the lower ends of said posts and pivotally secured at their inner ends, brackets carried at the outer ends of said arms, connecting bars pivotally joined to said brackets, a flash board or plate pivotally and adjustably joined at the lower ends of said connecting bars and a block and tackle for raising and lowering said arms.

3. In flash boards for unloading apparatus, the combination with an unloading plow, of a pair of flash boards, a frame rigidly secured to the rear mold boards of said plow, a frame rigidly secured to the pilot mold boards of said plow, a frame pivotally secured to the aforesaid frames, arms extending outwardly from said pivot frame beyond each side of the plow, means for suspending said flash boards from said arms and means for raising and lowering said arms.

4. In flash boards for unloading apparatus, the combination with a plow having pilot and rear mold boards, of a plurality of flash boards or plates, a frame having uprights, cross and longitudinal bars and rigidly secured to said rear mold boards, a frame having uprights and a cross bar rigidly secured to said pilot mold boards, a frame having longitudinal and cross beams pivotally secured at its front end to said frame from the pilot, and intermediate of its length to said frame from the rear mold boards and posts extending upwardly centrally from the cross beams, a plurality of arms extending beyond the longitudinal of said pivoted frame at each side and pivotally secured at their inner ends, connecting bars extending from the outer ends of said arms and having pivotal connection therewith and adjustably supporting said flash boards or plates at their lower ends, and means ex- 130

tending from the upper ends of said posts to the outer end of said arms for raising and lowering the latter.

5. In flash boards for unloading apparatus, a frame having posts extending upwardly therefrom, said frame including a plurality of cross and longitudinal beams, supports for the frame, arms extending from the lower ends of said posts and pivoted at their inner ends, connecting bars pivotally joined to said arms, a flash board or plate pivotally joined to the lower ends of said connecting bars, a means for lowering said arms.
15. 6. In flash boards for unloading apparatus, a frame formed of cross and longitudinal beams, posts projecting upwardly therefrom, means for supporting the aforesaid frame, members extending from the lower ends of the posts and pivotally secured at their inner ends, brackets carried at the

outer ends of said members, connecting bars pivotally joined to the brackets, a flash board pivotally and adjustably joined at the lower ends of said connecting bars.

25

7. In flash boards for unloading apparatus, the combination with a loading plow of a pair of flash board frames rigidly secured to the molding boards of said plow, a frame pivotally secured to the aforesaid frames, 30 arms extending outwardly from said pivot frame beyond each side of the plow, means for suspending said flash boards from said arms and means for raising and lowering said arms.

35

Signed at the city of Montreal, Quebec, Canada, this 18th day of December, 1914.

ALFRED AYRE MELLOR.
